(Cl. 93—2)

This invention relates to methods and apparatus for the manufacture of sheaths, particularly of the portfolio type, for packing cigarette paper blocks. The invention is most particularly but 5 not exclusively concerned with cigarette paper sheaths in which the undermost portion comprises at its ends a number of side flaps folded between themselves and the block of paper, whilst the uppermost portion is provided with 10 an end flap which is inserted between the undermost portion and the lateral flaps, in such a way that the sheath will remain folded without any gumming.

A most important feature of the invention is 15 the insertion of the end flap between the undermost portion of the sheath and the flaps formed in this portion this insertion being performed as follows: After having previously folded down the lateral flaps, the end flap is urged between 20 said lateral flaps and the undermost portion, by means of insertion members arranged substantially parallel to said portion and this is done whilst the body of the sheath is pivoted for approaching said portion. The insertion members 25 may be formed by rods of reduced section which are preferably oscillatably supported. It is advantageous to provide the insertion members with sharpened points for gripping the cardboard of the end flap.

30 In one embodiment the insertion members are constituted by flat rods which are pivotally supported in order to form with respect to the undermost portion an angle which is decreasing as the insertion proceeds.

35 The lower lateral flaps may be folded down about a flat shaped mandrel against which said flaps are urged by the folding blades. The upper lateral flaps may be folded by means of pliers which grasp the block at its ends and pivot it 40 during the insertion of the end flap. The end flaps will be previously folded at right angles by means of fixed oblique members.

An advantageous arrangement for the insertion 45 of the first sheet in the aperture of the blank consists in raising said first sheet then imparting to the blank a translation motion which brings it against the paper block, whilst the first sheet will pass through the aperture. The first sheet will be advantageously raised by means of 50 a blade which strikes it and is preferably slightly displaced by its contact with the same.

It is understood that all the arrangements described above and below may be considered as 55 separately or jointly protected herewith.

55 By way of example and in order that the in-

vention may be fully understood, it will be described by reference to the accompanying drawings in which:

Figure 1 is an elevation view showing the cigarette paper block and the blank when the first sheet is raised. 5

Figure 2 is a plan view corresponding to Figure 1.

Figure 3 is a view similar to Figure 1 but at the beginning of the insertion of the first sheet 10 in the aperture.

Figure 4 is a view showing the position of the parts at the end of the insertion of the first sheet.

Figure 5 shows the block grasped between the 15 pressure members.

Figure 6 shows the beginning of the folding of the flaps.

Figure 7 shows the end of the folding of the flaps at right angles.

Figure 8 is a section view through a plane at 20 right angles to Figure 7.

Figure 9 shows the end of the folding step for the upper lateral flaps by means of the pliers.

Figure 10 shows the folding down of the lower lateral flaps. 25

Figure 11 is a section through a plane at right angles to Figures 9 and 10.

Figure 12 shows the beginning of the insertion of the end flap.

Figure 13 shows the end of said insertion. 30

Figure 14 is a plan view corresponding to Figure 13.

Figure 15 is an elevation view of the pliers for folding the upper lateral flaps, when at rest.

Figure 16 is an end view of the pliers seen by 35 the left side of Figure 15.

Figure 17 is an end view of the pliers seen by the right side of Figure 15.

Figure 18 is an elevation view of the pliers in 40 the opening position.

Figure 19 is a plan view corresponding to Figure 18.

Figure 20 is an end view of the pliers during their rotation, seen from the left side as in Figure 16. 45

Figure 21 is an end view of the pliers when they are in the position of Figure 20, but seen from the right side, as in Figure 17.

Figure 22 is a diagrammatic elevational view showing the main parts assembled. 50

Figure 23 is a front view corresponding to Figure 22.

Figure 24 is a perspective view of the book in the folding operation shown in Figure 13.

The invention has for its object to wrap a 55

block 1 formed by a pile of sheets of cigarette paper interfolded into a cardboard blank (Figure 2) in which is provided an aperture 2 from which the sheets of paper may be removed the 5 ones after the others as required for use.

The blank is cut in the form shown in Figure 2; it comprises from right to left, a portion 3 which will form the cover, a portion 4 which will be the undermost part of the sheath, an upper part 5 in which is provided the aperture 2 and finally the end flap 6. On the sides are provided the lower flaps 7, 8 and the upper flaps 9, 10. The dotted lines are the lines along which the parts will be folded.

15 The various steps for folding said blank about the sheath 1, will be hereafter described in their natural succession, as well as the parts which secure the folding operation. The said parts are shown in the figures which illustrate each of said 20 steps and they will at least partially be found in the Figures 22 and 23 which diagrammatically show the assembly of the machine.

At the beginning, the parts are in the position shown in said Figures 22 and 23. The block 25 1 bears upon a pressure member 11 and is maintained in this position by a plate 12. The blank is at a slightly higher lever since the flaps 7, 8, 9, 10 are supported by the cam pieces 13, 14 (Figures 22, 23, 1 and 2).

30 At this time a cutter 15 strikes the upper face of the block 1, substantially at its center. Said cutter is carried by the arm 16 supported by the shaft 17 which may slide in the guide 18. The rotation of the shaft 17 is followed by its displacement from right to left in its guide, so that the cutter 15 strikes the block 1 and is subsequently slightly displaced towards the left. This results in a deformation of the first sheet of the block which is turned up in the position shown 40 in Figure 1.

After this, the shaft 17 is rotated in the opposite direction, so that the cutter 15 is withdrawn and the plate 12 removed. A pressure member 20 causes the blank to slide from right to left on the cam surfaces 13, 14; the end 6 of the blank then 45 bears against a pin 21 (Figure 3) which is progressively depressed whilst the blank travels down along the slope 22 provided in front of the cam surfaces 13, 14, so that the blank will remain in 50 a horizontal position.

At that time, the first sheet 19 is in front of the opening 2, and will pass therethrough, as shown in Figure 3. At the end of said motion, the portion 5 of the blank is resting on the block 55 1, as will be seen in Figure 4, whilst the first sheet 19 emerges from the aperture 2.

At the end of such first step, which will be mentioned as the insertion of the first sheet, a pressure member 23 arranged at the top of the machine in Figures 22 and 23, is lowered vertically and pressed on the blank, as shown in Figure 5. Subsequently both pressure members 11, 23, are simultaneously raised together with the paper block and the blank. Along their path, the flaps 65 7, 8, 9, 10 engage the folding members 24, 25, (Figures 6 and 23) and are consequently folded at right angles; at the end of their travel, the flaps are in the position shown in Figures 7 and 8.

In front of the upper flaps 9, 10, come the folding pliers, which will be described below with reference to Figures 15 to 21; only the operative blades 26, 27, 28, 29, of said pliers are shown in Figures 7, 8 and 9. The pliers move towards the center of the block and are closed upon the same, 75 so that they fold down the upper flaps 9, 10 upon

the block in the position shown in Figure 9; this is easily performed since the folding members 24, 25, have a semicircular slot at their top, as will be best seen in Figure 11.

The lower flaps 7, 8, are then folded by the 5 folding blades 30, 31, which urge them against a steel plate 32 (Figure 10) bearing upon the lower face of the blank; the said steel plate or mandrel 32 has been brought in such position at the beginning of the above described phase, which will be called folding of the flaps. It should be mentioned that the cooperating motion of the said 10 folding members 30, 31, is obtained on account of the toothed sections 33, 34, integral with the levers 35, 36, carrying the folding members which 15 are articulated on the shafts 37, 38.

The insertion of the end flap will now be described. It should first of all be mentioned that each of the pliers which will be subsequently described is rotatable about an axis which is parallel to the plane of Figures 7, 9 and 10 and at right angles to the plane of Figures 3, 11, 12, 13; the shaft 40 is shown in elevation in Figure 23 and its end is appearing in Figures 8, 11, 12.

This phase of insertion takes place whilst the 20 above mentioned pliers are rotated 180° about their shaft 40. When the said pliers and the block which they have grasped are moved from the position shown in full lines in Figure 11, to the position shown in chain and dotted lines, an elongated member 41, shown at the bottom of Figure 11 comes into action; the said member 41 is raised and meets the end flap 6 of the blank which was in the position shown in chain and dotted lines in Figure 12; the end flap is thus lifted in the position shown in full lines in Figure 12 and the action of the member 41 will then cease.

This phase of insertion of the end flap 6 in itself is secured by the catches 42, 43; the said catches are constituted by sharp pointed members articulated 40 on a part 44 which is moved in parallel direction to the mandrel 32 and against its lower face. The part 44 is provided with lugs 45 (Figure 22) on which are supported the pivots 46 forming the articulations of the catches 42, 43, as will be best seen in Figure 22, the catches may be inclined 45 downwards of a defined angle and they can also be slightly raised above the horizontal plane.

At this phase of the process, the folding members 30, 31 are withdrawn in pivoting about the 50 axes 37, 38, so that the lower flaps 7, 8, are slightly removed from the mandrel 32, as shown in Figure 12. The part 44 is then displaced from right to left and the catches grasp the end flap 6 and insert it in the space provided between the mandrel 32 and the lower flaps 7, 8, whilst the folding pliers continue their rotation. This phase is shown in Figures 13, 14 and will be best understood with reference to Figure 24.

The pliers can easily complete their rotation 60 due to the reduced thickness of the catches 42, 43, and to the fact that they are linked at 46. At the end of said revolution the pliers are withdrawn, as well as the catches 42, 43, and the mandrel 32. The only thing to do now is to fold down the undermost portion 3 upon the top of the book, and this is very easily performed without any special means.

The folding pliers 26, 27, 28, 29, will now be described in detail, with reference to Figures 15 to 70 21. The said pliers are supported at the ends of the levers 47, 48, articulated on a pivot 49 in order to operate as scissors. The pivot 49 is arranged upon a block 50 provided at the end of a shaft which is rotatable and slidable upon a bear- 75

ing 52. On the side of the bearing 52 is attached a cam 53 which is best seen in Figure 18. The front ends of the levers 47, 48, are provided with projections 54, 55, which may engage the cam 53. A spring 56 is tending to close the pliers, but a stop 57 fixed to the shaft 51 will define said closing motion. At rest the pliers are in the position shown in Figures 15 and 23; in order to perform the folding step, the shaft 51 slides from left to right in its bearing, so that the projections 54, 55, act upon the cam 53, as shown in Figure 18; consequently, the pliers 28, 29, are spread aside and subsequently closed upon the block, as had been previously explained. The shaft 51 is then rotated in its bearing thus driving the pliers, and this corresponds to the insertion phase of the end flap. When the operation is completed, the shaft 51 slides back from right to left and removes the pliers from the manufactured block; since the projections are rotated 180°, they cannot meet the cam 53 in such displacement. Finally, the shaft 51 is rotated 180°, in order to come once more in the position shown in Figures 15, 16 and 17.

25 The pliers are operated by the rotation of the shafts 40, 51 (Figure 23) and by a lever 59 which will impart to the shaft 40 the longitudinal displacements; said displacements are transferred to the shaft 51 by a system of levers 60, 61, which 30 are articulated at 62 and 63.

Having now particularly described and ascertained the nature of my invention and in what manner the same is to be performed, I declare that what I claim is:

35 1. A process of folding a blank having a bottom portion, a top portion having a slot therein, a cover portion, an end flap, a pair of upper side flaps and a pair of lower side flaps comprising folding said pair of lower side flaps to a position adjacent said bottom portion and then moving said end flap to a position between said bottom portion and said folded lower side flaps.

2. A process of folding a blank having a bottom portion, a top portion having a slot therein, a cover portion, an end flap, a pair of upper side flaps and a pair of lower side flaps about an article comprising folding said upper side flaps about said article, then folding said pair of lower side flaps to a position adjacent said bottom portion, then rotating said article with said top portion, upper side flaps and end flap relative to said bottom portion and then moving said end flap to a position between said bottom portion and said folded lower side flaps.

50 3. A process of folding a blank having a bottom portion, a top portion having a slot therein, a cover portion, an end flap, a pair of upper side flaps and a pair of lower side flaps about an article comprising folding said upper side flaps about said article, then folding said pair of lower side flaps to a position adjacent said bottom portion, then rotating said article with said top portion, upper side flaps and end flap relative to said bottom portion, then moving said end flap to a position between said bottom portion and said folded lower side flaps and then folding said cover portion over the top portion.

70 4. A process of folding a blank having a bottom portion, a top portion having a slot therein, a cover portion, an end flap, a pair of upper side flaps and a pair of lower side flaps about a pack of interfolded cigarette papers comprising assembling said pack with said blank so that one end of the top cigarette paper on said pack extends through said slot, then folding said upper side

flaps about said pack, then folding said pair of lower side flaps to a position adjacent said bottom portion, then rotating said pack with said top portion, upper side flaps and end flap relative to said bottom portion, then moving said end flap to a position between said bottom portion and said folded lower side flaps and then folding said cover portion over said top portion.

5 5. An apparatus for folding blanks having a bottom portion, a top portion having a slot therein, a cover portion, an end flap, a pair of upper side flaps and a pair of lower side flaps comprising means for folding said pair of lower side flaps to a position adjacent said bottom portion, means for turning said top portion and end flap relative to said bottom portion and an insertion element having a pointed end for moving said end flap to a position between said bottom portion and said lower side flaps.

10 6. An apparatus for folding blanks having a bottom portion, a top portion having a slot therein, a cover portion, an end flap, a pair of upper side flaps and a pair of lower side flaps comprising means for folding said pair of lower side flaps to a position adjacent said bottom portion, means for turning said top portion and end flap relative to said bottom portion, an insertion element, said insertion element having pointed rods therein for inserting said end flap into a position between said bottom portion and said lower side flaps and means permitting a limited oscillation of said rods about an axis parallel to said bottom portion.

15 7. An apparatus for folding blanks having a bottom portion, a top portion having a slot therein, a cover portion, an end flap, a pair of upper side flaps and a pair of lower side flaps comprising means for folding said pair of lower side flaps to a position adjacent said bottom portion, means for turning said top portion and end flap relative to said bottom portion, a plate, means for reciprocating said plate horizontally, pointed rods carried by said plate for inserting said end flap between said bottom portion and said lower side flaps and means permitting said rods a limited oscillation about an axis parallel to said bottom portion.

20 8. An apparatus for folding blanks having a bottom portion, a top portion having a slot therein, a cover portion, an end flap, a pair of upper side flaps and a pair of lower side flaps, comprising a pair of folding plates for folding said pair of lower side flaps to a position adjacent said bottom portion, means for turning said top portion and end flap relative to said bottom portion, means for withdrawing said plates and means for then inserting said end flap between said bottom portion and said lower side flaps.

25 9. An apparatus for folding blanks having a bottom portion, a top portion having a slot therein, a cover portion, an end flap, a pair of upper side flaps and a pair of lower side flaps comprising means for folding said pair of lower side flaps to a position adjacent said bottom portion, means for turning said top portion and end flap relative to said bottom portion, a folding member for lifting the end flap and an insertion member for inserting such lifted end flap into a position between said bottom portion and said lower side flaps.

30 10. An apparatus for folding blanks having a bottom portion, a top portion having a slot therein, a cover portion, an end flap, a pair of upper side flaps and a pair of lower side flaps comprising means for folding said pair of lower side flaps to a position adjacent said bottom portion, means for turning said top portion and end flap relative to said bottom portion, a folding member for lifting the end flap and an insertion member for inserting such lifted end flap into a position between said bottom portion and said lower side flaps.

side flaps to a position adjacent said bottom portion, a pair of pliers for folding said upper side flaps about the articles wrapped, said pliers being mounted for oscillation about an axis adjacent the folding line between said bottom portion and said top portion.

11. An apparatus for folding blanks having a bottom portion, a top portion having a slot therein, a cover portion, an end flap, a pair of upper side flaps and a pair of lower side flaps comprising means for folding said pair of lower side flaps to a position adjacent said bottom portion, a pair of pliers for folding said upper side flaps about the articles wrapped, said pliers being mounted for oscillation about an axis adjacent the folding line between said bottom portion and said top portion, said pliers each comprising two blades capable of being operated so as to simultaneously move toward one another and also move towards the center of the folded blank thereby folding down the upper side flaps of said blank.

12. An apparatus for folding blanks having a bottom portion, a top portion having a slot therein, a cover portion, an end flap, a pair of upper side flaps and a pair of lower side flaps comprising scissors-like folding plates for folding said upper side flaps, means for folding said lower side flaps to a position adjacent said bottom portion, means for folding said top portion and end flap relative to said bottom portion and means for folding said end flap into position between said bottom portion and said lower side flaps.

13. An apparatus for folding blanks having a bottom portion, a top portion having a slot therein, a cover portion, an end flap, a pair of upper side flaps and a pair of lower side flaps, means for folding said pair of lower side flaps to a position adjacent said bottom portion, pivoted levers for folding said upper side flaps, said levers having fixed abutments thereon and a fixed cam cooperating with said abutment in order to open and close said levers to carry out the folding operations.

14. An apparatus for folding blanks having a bottom portion, a top portion having a slot

therein, a cover portion, an end flap, a pair of upper side flaps and a pair of lower side flaps comprising means for folding said pair of lower side flaps to a position adjacent said bottom portion, a rod located parallel to the longitudinal length of the blank being folded, folding pliers mounted upon said rod for folding the upper side flaps and means for rotating and reciprocating said rod in order to carry out the folding operations.

15. An apparatus for folding blanks having a bottom portion, a top portion having a slot therein, a cover portion, an end flap, a pair of upper side flaps and a pair of lower side flaps comprising a pair of folding pliers, means for operating said pliers so as to fold certain flaps, means for rotating said pliers in order to fold said blank along a longitudinally extending fold and means for moving said pliers toward and away from said blank.

16. An apparatus for wrapping blanks having a bottom portion, a top portion having a slot therein, a cover portion, an end flap, a pair of upper side flaps and a pair of lower side flaps about a pile of cigarette papers comprising a reciprocating bar cooperating with the topmost cigarette paper on said pile in order to raise one end thereof, means for moving said blank relatively to said pile so that said topmost cigarette paper is inserted in said slot in said top portion and means for thereafter folding said wrapper about said pile of cigarette papers.

17. A process of forming a pile of sheets of paper in a wrapper having a window comprising forming a pile of sheets of paper, raising at least a portion of the first sheet thereon, then introducing the raised portion of said first sheet into the window of said wrapper by a relative displacement of said wrapper in a rectilinear line in a plane substantially parallel to the raised portion of said first sheet.

18. A process according to claim 17 wherein said portion of said first sheet is raised by contacting said first sheet with a blade moving parallel to itself in a plane parallel to said first sheet prior to the raising of a portion thereof.

HENRI CHAMBON.
